FILM DRYING MACHINE

Millard E. Long, San Antonio, Tex., assignor to
Carl D. Newton, San Antonio, Tex.

Application March 29, 1930. Serial No. 440,106

1 Claim. (Cl. 34—12)

This invention relates to a device for drying photographic films, the general object of the invention being to provide means whereby a large quantity of films can be easily and quickly dried by passing them through a drying chamber at the proper speed, with means for controlling the temperature, direction of flow and the humidity of the air passing through the chamber.

10 A further object of the invention is to provide means for removing surplus water from the films before they enter the chamber.

This invention also consists in certain other features of construction and in the combination and arrangement of the several parts, to be hereinafter fully described, illustrated in the accompanying drawings and specifically pointed out in the appended claim.

In describing the invention in detail, reference will be had to the accompanying drawings wherein like characters denote like or corresponding parts throughout the several views, and in which:—

25 Figure 1 is an elevation of the invention.
Figure 2 is a view of one end thereof.
Figure 3 is a section on line 3—3 of Figure 1.
Figure 4 is a section on line 4—4 of Figure 1.
Figure 5 is an elevation, partly in section, showing a modification.

30 In these drawings, the numeral 1 indicates a housing having its sides and top closed and its ends open, except the lower parts thereof, as shown at 2. An extension 3 projects from one end of each side of the housing an appreciable distance from the top and each extension supports the bearings for a stub shaft 4, the inner end of which carries a sprocket 5. Stub shafts 6 are arranged at the other end of the housing and carry on their inner ends the sprockets 7. 40 An endless chain 8 passes over each pair of sprockets 5 and 6 so that the chains parallel each other and are spaced apart so as to support the bars 9 to which the films 10 to be dried are attached by the clips 11. The bars are supported at their ends by the chains. Thus the bars carrying the films are moved through the housing from one end to the other by the chains. The chains are driven from a motor 12 through the sprockets and chains, shown generally at 13, with the last chains passing over sprockets on the shaft 6.

45 A heater 14 of any desired type and controlled by a thermostat 15 is used to heat air supplied to the same from a fan 16 operated by a motor 17, the air being delivered to the heater from

the fan through a pipe 18 and the air from the heater is delivered to the housing by the distributor pipes 19 which discharge into different parts of a chamber 20 formed in the bottom of the housing by a horizontally arranged perforated plate 21. Thus the heated air will pass upwardly from the perforations and contact the films as they are conveyed through the housing by the chains.

50 A discharge pipe 22 has its horizontal portion connected with the top of the housing at different points by the ducts 23 and the vertical part of the pipe conducts the heated air to the exterior of the building in which the device is placed. A pipe 24 connects the central part of 60 the horizontal part of the pipe 22 with the intake of the fan 16 and this pipe 24 is provided with an opening 25 controlled by a slide or damper 26. The opening 25 is in communication with the room or building in which the device is placed so that when the damper is opened or partly opened, the air from the room will be drawn into the circulating system which will lessen the amount of air taken from the pipe 22 and thus permit more of the moisture laden 65 air from the housing to escape to the atmosphere from the pipe 22. As the air drawn into the opening 25 is taken from the room, this air has less moisture in it so that by means of the damper 26, the amount of moisture in the heated 70 air passing through the housing can be controlled.

75 A motor driven fan 27 is supported from the device above the front end of the conveyor so that surplus moisture on the films will be removed by this fan before the films enter the housing.

80 The film carrying bars are delivered to the diagonally arranged conveyors 28 at the rear end of the housing, as these chains are arranged to receive the bars from the chains 8 and these chains 28 deliver the bars on the shelves 29. The chains 28 are held taut by the springs 30 which are connected with the shelves 85 and these shelves are pivoted to the rear part 90 of the device, as shown at 31.

95 Thus it will be seen that as the films are conveyed through the device, they are subjected to the drying effect of the heated air so that they are dried before they reach the rear end of the device. The speed with which the films are conveyed through the device can be regulated and the moisture contents of the air used in drying the films can be controlled by 100 the damper 26.

If desired, an arrangement similar to that shown at the rear end of the device can be used to deliver the film carrying bars to the conveyor chains 8.

- 5 The arrangement of the delivery pipes 19 and the perforated plate 21 insures an even distribution of the heated air throughout the housing.

In the modification shown in Figure 5, some 10 of the heated air is delivered into a chamber 32 at the top of the front end of the housing by means of the pipes 19'. As the bottom of this chamber is perforated, as shown at 33, this air will be directed downwardly and it will be drawn 15 through the perforated plate 34 at the bottom of the front part of the housing and through the pipes 35. Some of the air is delivered in the lower chamber 36 at the rear part of the housing and after passing through the perforations 37, will pass upwardly through the housing and pass from the top of the same 20 through the pipe 38. Thus in this form of the device, the air flows downwardly in the front part of the housing and upwardly in the rear 25 part thereof.

It is thought from the foregoing description that the advantages and novel features of the invention will be readily apparent.

It is to be understood that changes may be 30 made in the construction and in the combination and arrangement of the several parts, provided that such changes fall within the scope of the appended claim.

What I claim is:—

35 A photographic film drying device of the

character described; comprising a housing having opposite partly open inlet and outlet ends, twin conveyor means arranged interiorly of the housing close to opposite sides thereof and extended through and beyond the inlet end, means for delivering a drying medium within the housing and at separated intervals of said conveyor means, surplus moisture removing means overhanging the extended conveyor means at the inlet end of said housing, a conveyor bar cross-wise of the twin conveyor means for carriage of films between the twin conveyor means, a shelf arranged at the outlet end of the housing and having separated portions to accommodate films therebetween upon the bar, inclined conveyors having connection with the shelf and located between the same and the twin conveyor means and inclined away from the latter in the direction of the shelf, flights on the last named conveyor for receiving the bar from the twin conveyor means, means for tensioning the separated portions to prevent sagging of the inclined conveyors, and a driving train arranged exteriorly upon the housing and connected through opposite sides thereof with the twin conveyor means and the inclined conveyors, the shelf constituting an automatic receiver for the bar and releasing the latter from the flights of the inclined conveyors, said twin conveyor means, inclined conveyors and separated portions of the shelf being close to each other at the outlet end of the housing.
